UNITED STATES PATENT OFFICE.

JULIAN R. BRANDON, JR., OF SAN FRANCISCO, CALIFORNIA.

CONDENSER FOR RADIATORS.

1,351,891.

Specification of Letters Patent. Patented Sept. 7, 1920.

Application filed June 6, 1918. Serial No. 238,455.

To all whom it may concern:

Be it known that I, JULIAN R. BRANDON, Jr., a citizen of the United States, and a resident of the city and county of San Francisco, State of California, have made a new and useful invention—to wit, Condensers for Radiators; and I do hereby declare the following to be a full, clear, concise, and exact description of the same.

10 The invention relates particularly to condensers for the radiators of an internal combustion motor and more particularly for radiators on motor vehicles.

15 Among the objects of the invention are to conserve the water supply of the radiator by avoiding the wastage thereof by evaporation, ejection through the overflow pipe due to expansion by heat, and by gravity when the vehicle descends steep inclines. 20 Other objects and advantages will appear as this description progresses.

25 In this specification and the annexed drawings, the invention is illustrated in the form considered to be the best but it is to be understood that the invention is not limited to such form, because it may be embodied in other forms, and it is also to be understood that in and by the claims following the description it is desired to cover 30 the invention in whatever form it may be embodied.

In the accompanying one sheet of drawings:

35 Figure 1 is a diagrammatic representation of a radiator of a motor vehicle having this invention applied thereto.

Fig. 2 is an enlarged detail in side elevation of a device constructed in accordance with this invention.

40 Radiators of this class comprise a substantially annular water receptacle having the conventional radiator cap 1, adapted to be screwed upon the neck 2 of the radiator 3, and having attenuated water passages 45 theracross, between which air is circulated to absorb the heat radiated by the water contained within said passages. Water cooled in the radiator descends and is pumped out near the bottom, circulated 50 through the internal combustion motor and returns to the top of the radiator at increased temperature owing to the heat absorbed from the motor. If the cold radiator is filled with cold water, it is obvious that

the water becoming expanded by the absorption of heat would burst the radiator unless overflow means were provided. When this invention is applied to a radiator, it is necessary to plug or remove the usual overflow pipe, to compel any overflow 60 to pass through the device.

In detail the construction of the invention illustrated in the drawings includes a continuous length of tubing having its lower end threaded as at 4 and passed 65 through a hole formed centrally in the cap 1. Continuing upward the tubing is bent into the succession of upwardly directed coils 5, terminating in the downwardly extending extension 6 provided with the compression coupling 7 joining it to the overflow pipe 8 carried down the radiator or disposed in any suitable or convenient manner to carry the overflow from the radiator. To prevent vibration of the coils 5, I interpose the non-heat-conducting base 9, preferably cylindrical in form and hollowed at the base to provide the concentric edges as at 10 to rest on top of the cap 1. The concave bottom accommodates itself to the 70 convex top of the cap 1. The lock nut 11 threaded on the tube 4 bears against the gasket 12 to seal the center opening in the cap and hold the base 9 snugly thereagainst. The upper extension of the base 9 is flattened 75 to form the supports 13 and 14 notched at their outer edges to receive the coils 5 and separate them the desired distance to prevent conduction of heat, prevent vibration and interspace the coils to 80 permit free circulation of air thereabout. The flat portion of the support is provided with the central opening, as at 15, so that the support presents the minimum amount 85 of resistance to the circulation of air about the coils. The terminal coil is attached to the top of the support member by the strap 16 fixed thereto and engaging the coil. When it is desired to remove the cap 1 to refill the radiator, the coupling 7 is opened, 90 separating the tubes 6 and 8, and permitting the rotation of the cap.

The coils 5 are wound about a suitable mandrel to give them the desired shape, which is preferably elliptical as illustrated 105 in Fig. 1. The extension 4 is then passed down through the central opening in the base 9, the flattened portions 13—14 lying

lengthwise of the coil. The base 9 is then given a quarter turn, which causes the notches in the supports 13—14 to engage their respective coils with sufficient tension 5 to prevent vibration of the coils and hold them in separated relation, as described. The strap 16 is then fastened in place and the condenser is fully assembled, giving a very simple, compact, effective and ornamental construction. The base and the supports 10 13—14 may be formed integrally of any suitable composition such as vulcanized compounds containing a large percentage of asbestos or other heat nonconducting material. The coils 5 are preferably formed of 15 seamless drawn copper tubing nickel, enameled or finished to suit the taste of the user.

This invention operates substantially as follows: Presuming the condenser to be applied to the radiator of an automobile. If the cold radiator is filled with cold water to full capacity, the first result following the operation of the motor is to expand the 20 water by absorbed heat from the motor, the surplus being ejected through the pipe 4, coils 5, and the waste pipe 8, relieving the radiator from the internal pressure or expansion of the water therein. Should the water in 25 the radiator rise to the boiling point, the steam or vapor generated would eject a certain amount of the water contained within the coils 5 through the overflow pipe 8. Subsequent or continuous generation of 30 vapor would rise into the coils 5 and be cooled therein, by giving off its heat to the air passing externally between and over the coils 5. The cooling results in the condensation of the vapor, which will drain back 35 into the radiator in the form of water. This effect continues during the normal operation of the vehicle. When an incline is encountered the water level may be lowered in the 40 radiator because of the body of water settling back into the water jackets and other spaces surrounding the motor, the usual quantity continuing to circulate by thermosiphon circulation or the operation of a force pump when the same is installed in the 45 piston. The receding of the water from the radiator will cause a momentary suction through the coils 5, drawing into the radiator any water or vapor that may be contained therein. When a decline is encountered 50 by the vehicle the water immediately and sometimes violently rushes forward into the top of the radiator, gushing out through the usual overflow pipes, if they are present, resulting in a considerable loss of water. 55 Where this invention is installed, the usual 60 overflow pipes are plugged or absent.

Having thus described my invention, what

I claim and desire to secure by Letters Patent is:

1. In combination with the removable cap 65 of a radiator, a tubular helix coil having its inlet end fixed in said cap and open to the interior of the radiator and extending exteriorly thereabove and having a descending overflow tube terminating below the top of 70 said radiator, and a base fixed to said cap having notched supports thereon engaging the coils of said helix.

2. In combination with the removable cap 75 of a radiator, a tubular helix coil having its inlet end fixed in said cap and open to the interior of the radiator and extending exteriorly thereabove and having a descending overflow tube terminating below the top of 80 said radiator, and a base fixed to said cap having notched supports thereon engaging the coils of said helix; and a strap fixed to said supports and engaging said overflow tube.

3. In combination with the removable cap 85 of a radiator, a tubular helix coil having its inlet end fixed in said cap and open to the interior of the radiator and extending exteriorly thereabove and having a descending overflow tube terminating below the top of 90 said radiator; and a base encircling said inlet end of said coil and having a flattened body with a lateral opening therethrough, and notched edges engaging the coils of said helix. 95

4. In combination with the removable cap of a radiator, a tubular helix coil having its inlet end fixed in said cap and open to the interior of the radiator and extending exteriorly thereabove and having a descending 100 overflow tube terminating below the top of said radiator; and a non-heat-conducting base encircling said inlet end of said coil and having a flattened body with a lateral opening therethrough, and notched edges engaging 105 the coils of said helix.

5. In combination with the removable cap of a radiator, a tubular helix coil having its inlet end threaded and extending through said cap and open to the interior of said 110 radiator, and extending exteriorly thereabove; a base engaging said inlet tube above said cap and drawn thereagainst by a nut threaded on said inlet and bearing against said cap; said base having a support thereon 115 engaging and separating the coils of said helix.

In testimony whereof, I have hereunto set my hand at San Francisco, California, this 20th day of May, 1918.

JULIAN R. BRANDON, JR.

In presence of—

BALDWIN VALE,

LINCOLN V. JOHNSON.
